UNITED STATES PATENT OFFICE

2,575,875

HIGH-TEMPERATURE GAS VALVE

Fred H. Johnson, Pittsburgh, Pa., assignor to
United States Steel Company, a corporation of
New Jersey

Application January 20, 1948, Serial No. 3,329

8 Claims. (Cl. 251—159)

1

This invention relates to valves for controlling flow of high temperature gases and particularly to water cooled closure disks embodied in such valves.

An object of the invention is to provide gas valve closure disks having improved and highly efficient means for circulating cooling water therethrough.

A further object of the invention is to provide improved gas valve closure disks of metal construction in which the exposed faces are insulated with refractory material for protection against high temperatures.

A further object of the invention is to provide improved valve closure disks of simplified construction having continuously water cooled sealing means for engagement with valve seats.

In accomplishing these and other objects of the present invention, I have provided improved details of structure, a preferred form of which is shown in the accompanying drawing, wherein:

Figure 1 is a vertical sectional view through a gas valve having a closure disk embodying features of the present invention.

Figure 2 is an enlarged vertical sectional view of a portion of the closure disk shown in Figure 1.

Figure 3 is a top plan view with parts cut away, illustrating a portion of the improved closure disk.

Referring more in detail to the drawing:

In Figure 1 there is shown at 10 a portion of a valve body adapted to control flow of hot gases, as for example the hot air blast to a metallurgical blast furnace. The body contains an annular seat 12. Said seat and body may be of any conventional design and hence are not shown nor described in greater detail.

A closure disk 13, constructed in accordance with the present invention, is cooperable with the upper face of seat 12 to close the valve against flow of gases. Disk 13 is fixed to the lower end of a stem 14 which may be raised and lowered by any suitable external operating mechanism, not shown.

As best shown in Figure 2, disk 13 comprises a hollow annular pipe 15 which extends around the circumference of the disk and is tangentially engageable with seat 12 to seal the valve. Said pipe has a circumferential opening in its upper region, opposite its seating region. A lower dome shaped plate 16 is joined to the inner circumferential edge of the opening in the pipe, and an upper cone shaped plate 17 is joined to the outer circumferential edge. The lower end of stem 14 is joined to upper plate 17. Stem 14 is tubular and

2

carries a concentric water inlet tube 18 which terminates slightly above plate 16. A central dome shaped baffle 19 is fixed to the lower end of tube 18 and at its circumference carries a circular flange 20 which extends downwardly within pipe 15 through the circumferential opening and defines water inlet and discharge orifices.

As best shown in Figure 3, a plurality of radial vanes 21 extend out from tube 18 between baffle 19 and plate 16, and similar radial vanes 22 extend between baffle 19 and plate 17. Both sets of radial vanes terminate approximately in line with the circumferential edge of plate 18. The radial vanes function both to position dome shaped baffle 19 between plates 16 and 17 and to direct flow of cooling water through the disk.

For cooling the valve water is introduced through tube 18 and flows through the passages which are defined by lower plate 16, baffle 19 and radial vanes 21 and then into pipe 15. The water is discharged from pipe 15 via the passages which are defined by upper plate 17, baffle 19 and radial vanes 22 and then through stem 14. The cross-sectional area of tube 18 is at least as great as the total inlet orifice area from the lower passages into pipe 15, in order not to retard water circulation. Preferably the areas of the inlet and discharge orifices of pipe 15 are substantially equal. The flow of water thus continuously cools pipe 15 throughout its circumference.

A dome shaped insulation block 24 of refractory material is fixed to the underface of plate 16. A conical insulation block 25 of similar refractory material is fixed to the upper face of plate 17. Preferably pipe 15 carries external circumferential wings 26 and 27 for retaining said insulation blocks.

When the valve disk is seated against seat 12, pipe 15 may flex slightly at its juncture with lower plate 16 to furnish a close fit against the seat. The line of juncture may be "necked-down" slightly as indicated at 28 in Figure 2 to assist such flexing. However, any such flexing must not be of sufficient magnitude to crack insulation block 24.

From the foregoing description, it is seen that I have provided an improved closure disk for valves adapted to control the flow of high temperature gases. The valve disk has a highly efficient water circulating system in which all metal parts are continuously cooled and the exposed metal parts are protected insofar as possible by refractory insulation. The sealing means shown provides a complete seal against passage of gases when the valve is closed.

While I have shown and described but a single embodiment of the present invention, it is apparent that modifications may arise. Therefore I do not wish to be limited by the disclosure set forth but only by the scope of the appended claims.

I claim:

1. In a valve, a body, an annular seat in said body, a closure disk cooperable with said seat to close the valve, and a tubular stem joined to said disk for operating the valve, said closure disk including an annular pipe extending around the circumference of the disk and engageable with said seat and having a circumferential opening opposite its seating region, a pair of spaced plates joined to said pipe at the edges of said opening, one of said plates being joined to said stem, a tube carried within the bore of said stem, and a continuous baffle fixed to the end of said tube and disposed in spaced relation between said plates and having a continuous circumferential flange extending into said pipe through said opening, said baffle directing circulation of cooling water through said pipe uniformly throughout its circumference.

2. In a valve, a body, an annular seat in said body, a closure disk cooperable with said seat to close the valve, and a tubular stem joined to said disk for operating the valve, said closure disk including an annular pipe extending around the circumference of the disk and engageable with said seat and having a circumferential opening opposite its seating region, a pair of spaced plates joined to said pipe at the edges of said opening, one of said plates being joined to said stem, a tube carried within the bore of said stem, a baffle fixed to the end of said tube and disposed in spaced relation between said plates and having a circumferential flange extending into said pipe through said opening, and a plurality of radial vanes extending outwardly from said tube in the spaces between said baffle and said plates, said baffle and said vanes directing circulation of cooling water through said pipe.

3. In a valve, a body, an annular seat in said body, a closure disk cooperable with said seat to close the valve, and a tubular stem joined to said disk for operating the valve, said closure disk including an annular pipe extending around the circumference of the disk and engageable with said seat and having a circumferential opening opposite its seating region, a pair of spaced plates joined to said pipe at the edges of said opening, one of said plates being joined to said stem, a tube carried within the bore of said stem, a continuous baffle fixed to the end of said tube and disposed in spaced relation between said plates and having a continuous circumferential flange extending into said pipe through said opening, said flange directing circulation of cooling water through said pipe uniformly throughout its circumference, and insulation blocks of refractory material fixed to the outer faces of said plates.

4. In a valve, a body, an annular seat in said body, a closure disk cooperable with said seat to close the valve, and a tubular stem joined to said disk for operating the valve, said closure disk including an annular pipe extending around the circumference of the disk and engageable with said seat and having a circumferential opening opposite its seating region, a pair of spaced plates joined to said pipe at the edges of said opening, one of said plates being joined to said stem, a

water inlet tube carried within the bore of said stem, a baffle fixed to the end of said tube and disposed in spaced relation between said plates and having a circumferential flange extending into said pipe through said opening defining water inlet and discharge orifices, and a plurality of radial vanes extending outwardly from said tube in the spaces between said baffle and said plates and positioning said baffle, said baffle and said vanes directing circulation of cooling water through said pipe and discharging through said stem, the cross-sectional area of said water inlet tube being at least as great as the total inlet orifice area to said annular pipe.

5. In a valve, a body, an annular seat in said body, a closure disk cooperable with said seat to close the valve, and a tubular stem joined to said disk for operating the valve, said closure disk including an annular pipe extending around the circumference of the disk and engageable with said seat and having a circumferential opening opposite its seating region, a pair of spaced plates joined to said pipe at the edges of said opening, one of said plates being joined to said stem, a tube carried within the bore of said stem, a baffle fixed to the end of said tube and disposed in spaced relation between said plates and having a circumferential flange extending into said pipe through said opening defining water inlet and discharge orifices, and a plurality of radial vanes extending outwardly from said tube in the spaces between said baffle and said plates and positioning said baffle, said baffle and said vanes directing circulation of cooling water through said pipe, the line of juncture between said pipe and one of said plates being necked-down slightly to permit flexing.

6. In a valve, a body, an annular seat in said body, a closure disk cooperable with said seat to close the valve, and a tubular stem joined to said disk for operating the valve, said closure disk including an annular pipe extending around the circumference of the disk and engageable with said seat and having a circumferential opening opposite its seating region, a pair of spaced plates joined to said pipe at the edges of said opening, one of said plates being joined to said stem, a water inlet tube carried within the bore of said stem, a baffle fixed to the end of said tube and disposed in spaced relation between said plates and having a circumferential flange extending into said pipe through said opening defining water inlet and discharge orifices, and a plurality of radial vanes extending outwardly from said tube in the spaces between said baffle and said plates and positioning said baffle, said baffle and said vanes directing circulation of cooling water through said pipe and discharging through said stem, the cross-sectional area of said water inlet tube being at least as great as the total inlet orifice area to said annular pipe, the line of juncture between said pipe and one of said plates being necked-down slightly to permit flexing.

7. A valve disk and stem combination comprising an annular pipe extending around the circumference of the disk and having a seating region which is adapted to engage a valve seat and a circumferential opening opposite its seating region, a pair of spaced plates joined to said pipe at the edges of said opening, the stem being tubular and one of said plates being joined thereto, a tube carried within the bore of the stem, and a continuous baffle fixed to the end of said tube and disposed in spaced relation between said plates and having a continuous circumferen-

tial flange extending into said pipe through said opening, said baffle directing circulation of cooling water through said pipe uniformly throughout its circumference.

8. A valve disk and stem combination comprising an annular pipe extending around the circumference of the disk and having a seating region which is adapted to engage a valve seat and a circumferential opening opposite its seating region, a pair of spaced plates joined to said pipe at the edges of said opening, the stem being tubular and one of said plates being joined thereto, a tube carried within the bore of the stem, a baffle fixed to the end of said tube and disposed in spaced relation between said plates and having a circumferential flange extending into said pipe through said opening, and a plurality of radial vanes extending outwardly from said tube in the spaces between said baffle and said plates, said baffle and said vanes directing 20 circulation of cooling water through said pipe.
